UNITED STATES PATENT OFFICE.

LEOPOLD POLLOCK, OF BROOKLYN, NEW YORK.

CHECK PROTECTOR.

Application filed April 28, 1926. Serial No. 105,060.

This invention relates to a device for destroying the smooth surface of paper or the like and deals more specifically with a device commonly known as a check protector. This protector is designed to so mutilate the portions of a negotiable instrument, for example, where there is likely to be unlawful alterations in the writing, that no further writing on such portions is possible after the instrument has been operated upon by this device. This result is obtained without rendering the original writing illegible.

An object of the invention is to provide a paper mutilating device which will be cheap to construct and thereby fill the need for an inexpensive protector.

Another object of the invention is to so construct the protector that it may be conveniently carried on the person, for example, on a key ring.

Other objects of this invention will in part be obvious and in part hereinafter pointed out.

The invention accordingly consists in the features of construction, combinations of elements and arrangement of parts which will be exemplified in the construction hereinafter described and of which the scope of application will be indicated in the following claims.

In the accompanying drawing, in which is shown one of the various possible illustrative embodiments of this invention,

Fig. 1 is a perspective view of a device embodying the invention showing its approximate size.

Fig. 2 is an enlarged plan view thereof.

Fig. 3 is a vertical sectional view taken along the center line of Fig. 2.

Fig. 4 is a fragmentary perspective view of a modified form of the improved device.

Fig. 5 is a view of a sample check showing how the device renders alteration of the same impossible after it is prepared by the maker.

Referring to the drawing, 10 denotes a check protecting device embodying the invention which is seen to comprise plates 11 made of any suitable resilient material, each plate being preferably stamped in one operation from sheet material to have depressed edge

portions 12; a slot 11^a; a lug 13; and an opening 13^a; projections 14; and the guiding end portions 15. These plates 11 are all of identical shape and size and any two of them may be assembled in a cooperating relation with the portions 12 coinciding and the lug 13 entered into the openings 13^a. Rollers or die

members, one male 16 and the other female 17, are mounted in the plates 11 by being journaled between the projections 14. The surface of the rollers may be formed with any convenient serrations, channels, pyramids or corrugations which properly mesh for destroying the smooth surface of a paper or a check passed between them. Devices such as these are well known in the art and for the purposes of this invention need not be explained further. Intermediate between the spring plates is placed the slide 19 having the projecting lugs 20 which register with slots 11^a and thereby serves the double function of retaining the slide against lateral movement and also of enabling the slide to be properly positioned with respect to the dies 16, 17 by the hand of the user of the device.

It is highly desirable to provide the protector with a sharp instrument such as a pen knife, for example, and such instrument must be completely shielded when not in use, for the reason that the present device is designed to be carried in the pocket. To this end, the rear portion 19^a of the slide 19 is formed in any well understood manner, preferably as shown to function as a pen knife.

A rivet 21 passing through the plates 11 between the portions 12 firmly joins the plates together and in view of the fact that said portions 12 are offset, the remaining oppositely disposed portions of the plates are normally positioned in spaced relation. The lateral displacement of the plates 11 is prevented by the engagement of the lugs 13 in the openings 13^a as is clearly seen from Figs. 1 and 2. The die members 16 and 17 are thus normally held apart to permit the insertion between them of a sheet or sheets of paper to be operated upon. The material of the plates 11 is of such resiliency that the pressure of the hand of the user may readily bring said die members into cooperative relation to operate upon the sheet of paper in the well understood manner.

A bail or ring 22 may be provided preferably being anchored by the rivet 21 to enable the device to be attached to a key ring, chain or the like.

In the modification shown in Fig. 4, the relation of the parts is the same as in the preceding figures except that the lugs 13 and openings 13^a are eliminated and the flattened collar or band 25 is placed over the plate ends 21 passed therethrough. This gives a rigid

structure and precludes the shifting of the plates laterally.

The operation of the device is as follows: The check is inserted between the guides 15 and the slide is moved so that the edge of the check abuts the leading edge of the slide 19 when the portion to be mutilated is between the rollers. The plates 11 are now pressed together, and the protector and paper are moved relatively until the portion to be mutilated has been passed between the rollers. The rear portion 19^a of slide 19 is provided with a slot 19^b through which the rivet 21 is received to allow sliding movement of slide 19 and also to cooperate with lugs 20 and restraining slide 19 from lateral movement. The edge of the slide serves to guide the movement. When the desired mutilation is obtained the paper may be withdrawn by releasing the pressure on the plates.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:

1. A device for mutilating a sheet of paper which comprises a pair of rotatable die members yieldably mounted for movement into and out of cooperative relation, and a gage 40 slidable relative to said dies, to guide said

sheet in relation to the dies and to maintain said dies normally in slightly spaced relation.

2. A device for mutilating a sheet of paper which comprises a pair of cooperating die members, a slide carried by said device adjustable with respect to said die members and serving to space said members normally slightly apart, and adapted to guide the sheet in the movement of the sheet in the device, and means to move said slide into position.

3. A device for mutilating a sheet of paper which comprises a pair of spring members joined at one end and having the other ends free for resilient movement toward each other, a mutilating roller mounted on each of said free ends, said rollers being retained normally out of contact and adapted to be pressed into cooperative relation, and a guide for said sheet of paper provided by the inner edge of a tool slidably retained between and adapted to be housed by said spring members.

4. A device for mutilating a sheet of paper which comprises a pair of resilient members joined together at one end and having the other ends free, each of said members having a longitudinally disposed slot, a pair of rotatable die members journaled in the free ends of said members, a plate adapted to be projected from between said members having a projecting lug on both sides thereof, said lug being slidable in said slots, and a guiding edge on one end of said slide.

5. A device for serrating paper which comprises a pair of similar slotted members, a rotatable die member mounted on each of said slotted members, and a gage slidably mounted between the slotted members and guided by the slots therein.

In testimony whereof I affix my signature.

LEOPOLD POLLOCK.
